TIRE CONSTRUCTION

Bernard E. Mendelsohn, Brookline, Mass., assignor, by direct and mesne assignments, of forty-two and one-half per cent to B. Howard Benson, Boston, Mass., and fifteen per cent to Irving Fisher, New Haven, Conn.

Application March 19, 1942, Serial No. 435,359

5 Claims. (Cl. 152—342)

The present invention relates to an improvement in tire construction, particularly to a construction in which two chambers are formed separated from each other. Tire tubes of this general nature are principally used for the purpose of preventing sudden blow-outs, as for instance, when the shell or shoe breaks and the rubber wall of the inner tube explodes. Many accidents have occurred in this way. The use of inner chambers within the rubber wall tube or inner tubes within the same have aided materially in preventing the sudden escape of air from the tube and the danger occasioned by sudden blow-outs.

In one of the methods commonly employed, a so-called non-stretchable partition forms an air chamber away from the tread upon which the machine rides, so that when a blow-out occurs usually the non-stretchable partition is not pierced and this retains the air within it in spite of the blow-out for sometime, thus preventing a sudden unbalance of the machine while it is in motion.

One of the difficulties in construction of this type is that the inner partition of its very nature cannot be made as strong as the outer shoe and yet it is placed under the same terrific strain when blow-outs occur or when any break occurs, as for instance as is common in air-craft tires in poor landings where often the outer shoe breaks or gives way. In order to take up such terrific strain which may occur, it is preferable to permit the so-called non-stretchable partition to have some stretch, both in its peripheral dimensions about the wheel and in its lateral dimensions in sectional elements of the shoe.

The applicant has learned in the present invention upon careful study and experiments that even with these precautions, when a blow-out occurs, the inner chamber does not stand up well under the strain. Frequently the valve is ripped out from its hole in the rim of the wheel and the portion of the expansible rubber tube which rests against the rim is entirely torn away from it. The applicant has found that the valve is usually drawn inwardly through the hole in the rim because of the release of pressure within the tube when it fails. In this case, the ordinary partition in the tube does not remain in place but is, rather, forced outward from the rim, pulling the sides of the expansible tube in the base with it to such a point where the wall of the tube no longer furnishes a support. At this point the chamber which normally is supported by the rim of the wheel no longer has this support and the expansible portions of the inner tube are free to expand

in the area where atmospheric pressure already exists. The base chamber, therefore, breaks.

The aim of the present invention is to overcome these difficulties by providing a construction in which, after a break occurs, the base chamber at the rim which serves to lock the shoe upon the wheel, remains sufficiently supported so that it not only serves to prevent the entire collapse or escape of the air within the tube, but also to retain the rubber in the base against the rim of the wheel so that it cannot be exposed through the movement and expansion of the separating element between the two chambers formed within the tube.

15 The present invention also has the advantage that it retains the shoe upon the rim of the machine. This permits the rubber in the shoe to be usefully applied as a riding cushion and prevent twisting and cutting, as often occurs, when a machine has to ride upon a flat tire.

20 In the present invention special means are used for retaining the flexible partition in relatively the same place near the rim of the wheel. In this connection the present invention is an improvement in the device shown and described in my copending application, Serial No. 430,595, filed February 12, 1942.

25 The same system for valve inflation may be used in the means in this invention as in the prior copending application.

30 Further merits and advantages of the present invention over the prior art will be more clearly understood from the description in the rest of the specification when taken in connection with the drawing in which Figure 1 shows a central fragmentary section taken through the tire and rim in the region of the inflating valves and Figures 2 and 3 show enlargements of details.

35 In the figures, the usual shoe or outer shell of the tire is indicated by 2, which has its base or beads 1 and 1' resting on the rim 3 of the vehicle, which as indicated in the figures is of the drop rim type, but any other type of rim may be used equally as well.

40 45 Within the shoe 2, when the shoe is inflated and on the wheel, is an inner tube 4, which may be of the usual type filling out the shoe and extending all around its inner surface and into the base or well 5 of the rim. Within the inner tube 4 there is provided a complete tube of substantially non-stretchable material 6. This tube is positioned within the tube 4 well within the arc struck from the center of the well 5 from one tip 7 of the rim to the other tip 8 of the rim. While 50 the tube 6 is substantially non-stretchable as com-

pared with the rubber tube 4, nevertheless it does stretch with the application of pressure in a manner as will be explained more fully later in another part of the specification.

The tube 6 has its side wall elements 9 and 10 securely attached to and sealed to the inner walls of the inner tube 4. This may be done in any of the usual ways as for instance by buffing the wall of the inner tube 4 and cementing the side walls 9 and 10 of the tube 6 to the buffed walls of the inner tube 4. The tube 6 is provided with a one way valve 11 by means of which the chamber 12 within the tube may be inflated from the chamber 13 within the inner tube 4. The tube 6 is provided with air vents 21 and 22 positioned in the lower wall 24 of the tube 6 so as to permit air to freely circulate to the place or chamber 23 which is shut off by means of the tube 6 from the chamber 13. The chambers 12 and 23 however are at the same pressure since air can freely pass from one to the other. The inner portion 24 of the tube 6 may dip down slightly into the well of the rim.

The valve 11 may be provided with a spring 14 exerting a slight pressure to keep the valve 11 closed. The chamber 13 is inflated through the air conducting tube 15 sealed between the tube 6 in its side wall 10 and the wall of the inner tube 4. This air conducting tube 15 extends upward from the valve 16 which passes through an opening in the rim 3 and is sealed in the rubber wall of the inner tube 4.

The valve 16 does not ordinarily permit air to enter directly into the chamber 23 or the chamber 12, since the end of the valve is sealed by means of the air plug 17 which normally is set up tightly so that no air will come into or escape from the chamber 12, by means of the valve 16. When it is desired to deflate the chamber 12 and the chamber 23, the stem of the valve 16 may be removed and a proper tool inserted through it to loosen the air plug so as to permit air in the chambers 23 and 12 to escape through the plug opening 18. The inside wall of the inner tube 4 beyond the region in which the side walls 9 and 10 of the tube 6 are joined to it may be covered with a self sealing compound 20 which under ordinary circumstances will serve the usual purpose of sealing punctures which may occur through the rubber of the inner tube 4.

The tube 6 is of such a construction that the top section 25 and the side sections 9 and 12 may stretch to a reasonable extent. For this purpose these parts of the tube may be constructed of rubberized fabric built up in layers in such a way that the fabric is biased to permit both peripheral and lateral expansion of the tube in these sections of its fabric. For instance if the fabric in the section 25 has its threads running diagonally to the plane of the wheel, this fabric will stretch both in the plane of the wheel and laterally thereto and similarly the side portion of the tubes 9 and 10 will stretch substantially the same manner. A stretch of perhaps 10% to 20% may be permissible in these portions, although it is preferable to confine the stretch to less than this amount between a condition where the chamber 13 has the proper air pressure to the condition which occurs in a blow-out.

It should be noted that when a blow-out occurs, the wall portions 9, 10 and 25 of the tube 6 will be under increased strain due to the fact that these portions must necessarily hold the air within the chambers 12 and 23 when the air in the chamber 13 has escaped. In this case how-

ever the lower portion of the tube 24 has no increased strain placed upon it from the air within the chamber 12, since the chamber 23 is still inflated at the same pressure as the chamber 12.

The sections of the tube 24 however acts as an anchor and pulls back the lower ends of the walls 9 and 10 all around the periphery of the wheel. To secure the section 24 even more permanently in this position, this portion of the tube should be made with its fabric not laid on the bias with respect to the tube, but rather the threads should run substantially in the direction of the plane of the wheel and laterally to it and this section may be thicker than the top section 25. This may be accomplished by overlapping the fabrics in the base of the inner tube to provide a thicker non-stretchable portion on the inner side of the tube than on the outer side, these overlapping fabrics having threads running substantially in the plane of the wheel and transverse thereto. The fabric for this purpose may be a woven fabric if desired, with the weft and woof at right angles to each other. If therefore the weft of the fabric is substantially parallel to vertical planes through the wheel and the woof is at right angles to these planes, then the only stretch of the fabric will occur in the stretch of the threads which may be made very small. This construction will act to maintain the lower portions of the walls 9 and 10 in their position and will therefore tend to maintain the lower portions of the wall 4 in its original position, thus preventing the rubber from rising when a blow-out occurs. The lower portion 26 of the rubber tube 4 cannot be forced upward therefore between the tube 6 and the shoe, and it therefore will have rigid walls on all sides to retain it at all times in the same place. The only stretch on the section 24 in the tube 6 will be the endwise pull on this section by the sections 9 and 10, and this will be offset by properly strengthening the partition 24. A good effect however will also be gained if the partition 24 is of the same character as the rest of the portions of the tube 6.

In addition to the advantages herein set forth, the same advantages will also be retained in this construction as in that of my copending application mentioned above.

In the expression in the claims of the present application, the inner tube 6 is referred to as having an inner side and an outer side, the outer side in this case is the section of the tube that has the larger peripheral circumference, whereas the inner side is the section that has the smaller peripheral circumference.

Having now described my invention, I claim:

1. In combination with the rim of the wheel having a central well and with a pneumatic tire casing having beads with clamping surfaces facing the rim of the wheel on which the casing fits, an expansible inner tube adapted to be inflated to fill out the inner space of the casing, a substantially non-expansible flexible tube positioned in the base of the inner tube and partitioning said inner tube off in two sections, one section comprising a larger portion of the inner tube extending to the tread of the casing and the other portion comprising a smaller chamber extending well within the arc struck from the center of the well as a center across from one rim tip to the other, said non-expansible tube having a base portion curved radially inward in the base and having therein, free air vents to the portion of the inner tube positioned in the base of the rim the side walls of said non-expansible, flex-

ible tube being joined to the side walls of said
expansible inner tube.

2. In combination with the rim of a wheel and with a pneumatic tire casing having beads with clamping surfaces facing the rim of the wheel on which the casing fits, an expansible inner tube adapted to be inflated to fill out the inner space of the casing, a substantially non-expansible flexible tube having a top section extending across the inner tube from a point near the level of the rim edge from one side to the other side and having side walls joined to the side walls of the expansible tube adjacent the section of the tire casing which abuts against the rim of the wheel said non expansible flexible tube having a bottom section with a base portion curved radially inward in the base, said non-expansible tube partitioning by means of the top section of the non expansible tube said inner tube into two chambers, one of said chambers being formed by the space within said non-expansible tube and the space closed off by the non-expansible tube and the section of the expansible inner tube adjacent the rim of the wheel, said non-expansible tube having an air connecting passage to the space within the inner tube adjacent the rim of the wheel.

3. In combination with the rim of a wheel and with a pneumatic tire casing having beads with clamping surfaces facing the rim of the wheel on which the casing fits, an expansible inner tube adapted to be inflated to fill out the inner space of the casing, a substantially non-expansible flexible tube having a top section extending across the inner tube from a point near the level of the rim edge from one side to the other side and having side walls adhered to the side walls of the inner tube in sections of the casing adjacent the rim of the wheel said non expansible flexible tube having a bottom section with a base portion curved radially inward in the base, said non-expansible tube partitioning by means of the top section of the non expansible tube, said inner tube into two chambers, the base section of the non expansible tube having a free communicating passage with the space within the inner tube adjacent the rim of the wheel, the section of said non-expansible tube on the inner side being of substantially less stretchable material than the portion of the tube on its outer side.

4. In combination with the rim of a wheel and with a pneumatic tire casing having beads with clamping surfaces facing the rim of the wheel on which the casing fits, an expansible inner tube

adapted to be inflated to fill out the inner space of the casing, a substantially non-expansible flexible tube having a top section extending across the inner tube from a point near the level of the rim edge from one side to the other side and having side walls adhered to the side walls of the inner tube in sections of the casing adjacent the rim of the wheel said non-expansible flexible tube having a bottom section with a base portion curved radially inward in the base, said non-expansible tube partitioning by means of the top section of the non-expansible tube, said inner tube into two chambers, the base section of the non-expansible tube having a free communicating passage with the space within the inner tube adjacent the rim of the wheel, the section of said non-expansible tube on the base section being made of fabrics lapped over one another to provide a thicker non-stretchable portion on the inner side of the tube than on the outer side thereof.

5. In combination with the rim of a wheel and casing having beads with clamping surfaces facing the rim of the wheel on which the casing fits, an expansible inner tube adapted to be inflated to fill out the inner space of the casing, a substantially non-expansible flexible tube having a top section extending across the inner tube from a point near the level of the rim edge from one side to the other side and having side walls adhered to the side walls of the inner tube in sections of the casing adjacent the rim of the wheel said non-expansible flexible tube having a bottom section with a base portion curved radially inward in the base, said non-expansible tube partitioning by means of the top section of the non-expansible tube, said inner tube into two chambers, the base section of the non-expansible tube having a free communicating passage with the space within the inner tube adjacent the rim of the wheel, the section of said non-expansible tube on the base section being made of fabrics lapped over one another to provide a thicker non-stretchable portion on the inner side of the tube than on the outer side thereof.
